UNITED STATES PATENT OFFICE.

HUBERT M. GREIST AND EMANUEL J. BOYLER, OF NEW HAVEN, CONNECTICUT,
ASSIGNORS TO THE GREIST MANUFACTURING COMPANY, A CORPORATION OF
CONNECTICUT.

SEWING-MACHINE ATTACHMENT-HOLDER.

1,051,402.

Specification of Letters Patent. Patented Jan. 28, 1913.

Application filed April 4, 1912. Serial No. 688,461.

To all whom it may concern:

Be it known that we, HUBERT M. GREIST, a citizen of the United States, and EMANUEL J. BOYLER, a citizen of Canada, and both 5 residing at New Haven, in the county of New Haven and State of Connecticut, have invented or discovered certain new and useful Improvements in Sewing-Machine Attachment-Holders, of which the following is 10 a specification, reference being had therein to the accompanying drawing.

This invention relates to a sewing machine attachment holder comprising a foot portion adapted to be secured to the presser 15 bar of a sewing machine, and having a laterally extending arm which is frictionally embraced by a portion of a support on which the attachment proper may be either permanently or detachably mounted. If the attachment proper be detachably mounted on 20 said support different interchangeable attachments may be used in connection with a single support; or if the attachment proper be permanently secured to said support the latter may be removed and then be replaced 25 by a similar interchangeable support having a different attachment proper. The fact that the attachment support is frictionally engaged with the laterally extending arm 30 of the presser foot portion of the device enables the support to be adjusted laterally for the purpose of locating the attachments in different working positions relative to the needle of a sewing machine, and also 35 enables the attachments which are permanently fixed to their supports to be readily and quickly removed and replaced without loosening or tightening set screws.

In the accompanying drawing Figure 1 40 is a plan view of the improved holder having a wide hemmer removably mounted on the attachment support. Figs. 2 and 3 are opposite side views of the same. Fig. 4 is a plan view of the same, showing the 45 three parts thereof separated from each other. Fig. 5 is an enlarged detail section on line 5—5, Fig. 1. Fig. 6 is a plan view, similar to Fig. 1, but showing a narrower hemmer which is permanently secured to its 50 support.

Referring to the drawing, 12 denotes a presser-foot portion provided with a shank 13 by which it may be secured to the presser-bar of a sewing machine, and with a laterally extending arm 14, said arm being above

the plane of the bottom of said foot portion. The arm 14 is frictionally engaged by what may be termed a socket portion 15 of a forwardly extending support 16 on which the attachment proper 17 is mounted 60 in front of the said presser foot portion 12. To this end the said socket portion 15 is preferably formed with downwardly extending flanges 18, embracing the sides of said arm 14, and having, beneath the said 65 arm 14, inturned lugs 19. Also the upper part of said socket portion 15 is provided with an integral or struck-out spring tongue 20, the free end of which is bent downward slightly so as to press against the upper 70 surface of the arm 14, and thus, in coöperation with the in-turned lugs 19, serves to frictionally but securely retain the attachment support in working position, while permitting a ready lateral adjustment of 75 said support, if desired; and also permitting the said support to be conveniently placed in position or removed if it be desired to replace the support by a similar interchangeable support on which a different kind of 80 an attachment proper may be mounted.

If it be desired to removably mount the attachment proper on its support the latter will preferably be provided with a holding part or plate 21, riveted or otherwise permanently secured to the support 16, and having at its sides rearwardly converging lips 22 adapted to embrace the sides of the base portion of the attachment proper 17, and which sides are also slightly rearwardly 90 converging so that they will have a wedging fit between the said rearwardly converging lips 22. By virtue of this construction of the rearwardly converging lips 22 of the holding plate or part 21 the passage 95 of the work through the attachment will have a tendency, owing to its frictional drag, to tighten the attachment proper in place; while it is obvious that it may be quickly removed when it is desired to substitute a 100 different form of attachment proper therefor, by moving it forward, or toward the operator, thus loosening the wedging grasp of the spring lips 22.

Instead of detachably mounting the attachment proper on the support 16 said attachment proper may be permanently secured to said holder, as in the form of the invention shown in Fig. 6, as by riveting the said attachment proper to the said sup- 110

2
port. This construction will necessitate the removal of the support when a different form of attachment is to be applied to the holder, as when a hemmer of a different 5 width from that shown in Fig. 6, or a binder, braider or corder, is to be applied to the holder.

From the foregoing it will be understood that the invention provides a convenient 10 form of attachment holder with which different forms of attachments, as different widths of hemmers, or braiders or corders, may be readily used in connection with the holder; the construction of the parts being 15 such that one form of attachment may be quickly and conveniently substituted for another form when occasion demands; and the construction also being such that while the attachments will be securely held in working 20 positions they may be readily adjusted laterally relative to the needle of the sewing machine (the position of the needle being indicated by the opening 23 in the presser-foot) when desired. To facilitate adjustment or removal of the attachment support 25 the socket portion 15 thereof is preferably provided at its end with an upturned lug 24 to be grasped by the thumb and finger of the attendant.

30 Having thus described our invention we claim and desire to secure by Letters Patent:

1. A sewing machine attachment holder consisting of a foot portion adapted to be secured to a sewing machine presser-bar and 35 provided with a laterally extending arm which is above the plane of the bottom of said foot portion, combined with a support extending forward from said arm and having a part comprising yielding means 40 engaging said arm, and thus serving to retain said support in place frictionally, and an attachment proper mounted on said support forward of said foot portion.

45 2. A sewing machine attachment holder consisting of a foot portion adapted to be

secured to a sewing machine presser-bar and provided with a laterally extending arm which is above the plane of the bottom of said foot portion, combined with a support extending forward from said arm and 50 having a part comprising yielding means frictionally engaging the said arm, and an attachment proper detachably mounted on said support forward of said foot portion, said support having rearwardly converging 55 lips serving to hold said attachment proper in place.

3. A sewing machine attachment holder consisting of a foot portion adapted to be secured to a sewing machine presser-bar and 60 provided with a laterally extending arm which is above the plane of the bottom of said foot portion, combined with a support extending forward from said arm and having a part frictionally engaging the latter, 65 said frictionally engaging part comprising in-turned lugs beneath and a struck-out or integral spring tongue above, and an attachment proper mounted on said support forward of said foot portion. 70

4. A sewing machine attachment holder consisting of a foot portion adapted to be secured to a sewing machine presser-bar and provided with a laterally extending arm, combined with a support extending forward from said arm and having a part frictionally engaging the latter, and an attachment proper mounted on said support forward of said foot portion, said support having rearwardly converging lips between 80 which said attachment proper is frictionally and detachably held. 75

In testimony whereof we affix our signatures, in presence of two witnesses.

HUBERT M. GREIST.
EMANUEL J. BOYLER.
